UNITED STATES PATENT OFFICE

WILLIAM H. LANNING, OF DETROIT, MICHIGAN, ASSIGNOR TO WM. W. BLAKELY, OF DETROIT, MICHIGAN

HOLDDOWN FOR VEHICLES

Application filed May 9, 1927. Serial No. 190,002.

This invention relates generally to devices for holding merchandise such as vehicles and the like against movement during shipment, and refers more particularly to the means for anchoring such devices upon the floors of freight cars or other suitable carriers.

One of the essential objects of the invention is to provide a device of the type described in which the anchorage members are permanently maintained upon the leg portions of the tie members so as to be always accessible for quick attachment to the flooring of suitable carriers.

Another object is to provide a hold-down construction that comprises relatively few parts, that is strong and durable, and that can be manufactured at a comparatively low cost.

With the above and other objects in view, the invention consists of certain novel features of construction, combinations and arrangements of parts, as will be hereinafter more fully described and particularly pointed out in the appended claim.

In the accompanying drawing:

Figure 1 is a side elevation of a device embodying my invention applied to a vehicle.

Figure 2 is a perspective view of the hold-down device.

Figure 3 is a fragmentary sectional view through one of the leg portions of the tie member and associated anchorage plate.

Referring now to the drawing, 1 is a tie member, and 2 and 3 respectively are anchorage plates of a hold-down device embodying my invention. As shown, the anchorage plates are preferably formed of sheet metal, are flat, and are provided at spaced points thereof with apertures 4 for receiving suitable securing elements such as nails 5 for attaching the plates to the flooring 6 of a freight car.

The tie member 1 is preferably U shape in form and is preferably formed of heavy gage wire. The leg portions 7 of this tie member are preferably substantially parallel and extend through the central apertures 4 of the anchorage plates 2 and 3 respectively. Preferably the lower ends of these legs are upset as shown at 8 and 9, thereby providing upwardly tapered portions 10 and 11 respec-

tively, and rounded heads 12 and 13 respectively.

In the process of construction, the anchorage plates 2 and 3 are sleeved upon the leg portions 7, and the lower ends of said leg portions are subsequently upset as shown.

In use, the intermediate loop portion 14 of the tie member straddles a suitable part such as an axle 15 of a vehicle, and the anchorage plates 2 and 3 respectively are rigidly secured to the flooring 6 by means of the nails 5. When in this position the tapered portions 10 and 11 of the legs of the tie member constitute seats or bearings for the anchorage plates and fill the central apertures 4, thereby providing snug engagement between the parts when in use. Inasmuch as the tapered portions 10 and 11 extend a short distance above the heads 12 and 13, the retainer plates 2 and 3 will be spaced a short distance from the floor 6 when secured in place, thereby enabling suitable tools (not shown) to be positioned between the flooring and plates to pry the latter loose when it is desired to detach the hold-down devices from the flooring.

While it is believed that from the foregoing description, the nature and advantage of my invention will be readily apparent, I desire to have it understood that I do not limit myself to what is herein shown and described and that such changes may be resorted to when desired as fall within the scope of what is claimed.

What I claim as my invention is:

An all metal hold-down device formed from a single length of wire and sheet metal, the length of wire having leg portions and a connecting portion, the leg portions terminating at their lower ends in enlarged flat disk-like floor engaging portions and having frustro-conical portions rising from said floor engaging portions, the connecting portion being at the upper ends of the legs for engagement with a vehicle spring or axle, and the sheet metal resting on said floor engaging portions and having openings receiving the frustro-conical portions aforesaid.

In testimony whereof, I affix my signature.

WILLIAM H. LANNING. 100
